UNITED STATES PATENT OFFICE.

PHILIP ESTES, OF LEAVENWORTH, KANSAS.

IMPROVEMENT IN STEAM-BOILER FURNACES.

Specification forming part of Letters Patent No. 131,431, dated September 17, 1872.

To all whom it may concern:

Be it known that I, PHILIP ESTES, of the city of Leavenworth, in the county of Leavenworth and State of Kansas, have invented an Improved Steam-Boiler Furnace, of which the following is a specification:

My invention consists of an improvement in steam-boiler fronts and furnaces or fire-boxes, by which the sides and bridge-walls of such fronts, furnaces, or fire-boxes are rendered fire-proof; and an extra quantity of steam generated with the same quantity of fuel.

B is the boiler. B¹ is the boiler front. B² is the boiler-stand. F F are furnace-doors. S is center piece of boiler front. A A are ash-pits. H H are water-spaces, cast in the boiler front, used instead of fire-brick liners for the protection of the same and for generating steam, each connected with the recessed water-spaces C C C C in the boiler front. C C C are recessed water-spaces in front and rear of boiler. T T are water-tubes connecting the water-spaces C C in front with the water-spaces C C in rear of boiler. D is the mud-drum. P P are bridge-wall pipe or tube, connecting and securing the rear water-spaces together,

through which water passes from one to the other, forming a water-bridge wall and generating steam. S' S' are pipes passing over the boiler and connected therewith, through which the steam generated in the tubes T T and bridge-walls P P passes into the steam-chamber of the boiler; and P' P' are supply-pipes connecting the boiler underneath. c c c are caps bolted onto the water-spaces C C C in front and rear of boiler, and can be easily detached for the purpose of cleaning or resetting tubes.

Having thus described my invention, what I claim as new, and desire to secure by Letters Patent, is—

The water-spaces C C C C provided with the caps c c c, in combination with the water-spaces H H, hollow bridge-wall P P, pipes S' S' and P' P', and the connecting-tubes T T, all arranged in relation to the boiler, substantially as and for the purpose described.

PHILIP ESTES.
